DESIGN.

No. 31,031.

Patented June 20, 1899.

B. N. HAWES.

HYDROCARBON BURNER.

(Application filed May 22, 1899.)

Fig. 1.

UNITED STATES PATENT OFFICE.

BENJAMIN N. HAWES, OF WASHINGTON, DISTRICT OF COLUMBIA.

DESIGN FOR A HYDROCARBON-BURNER.

SPECIFICATION forming part of Design No. 31,031, dated June 20, 1899.

Application filed May 22, 1899. Serial No. 717,858. Term of patent 7 years.

To all whom it may concern:

Be it known that I, BENJAMIN N. HAWES, a citizen of the United States, residing in the city of Washington, District of Columbia, ⁵ have invented and produced a new and original Design for Hydrocarbon - Burners, of which the following is a specification, reference being had to the accompanying drawings, forming part thereof.

¹⁰ The leading or essential features of my design consist in the peculiar or characteristic shape of the mixer, the base, and retort, and more especially the top plate of said mixer and the oppositely-disposed jet-pipe supports thereon.

In the drawings, Figure 1 is a perspective view of the burner, and Fig. 2 is a top plan view thereof.

In the drawings the letter *a* represents the ²⁰ mixer, *b* the base-plate, and *c* the retort.

As shown in the drawings, the mixer is of substantially oval shape, with downwardly-inclined side walls *d*, having undulating lower edges, as indicated by the letter *e*, and laterally-extending ears *f*, resting upon corresponding ears *g* on short standards *h* on the base *b*.

²⁵ *i* represents a top plate, which conforms to the contour of the upper portion of the mixer

and forms a part thereof, which plate is ³⁰ formed with circular openings *j* and generally oblong openings *k*, having their sides parallel, the ends thereof next to the center of the plate being slightly curved, while the outer or opposite ends have slight inwardly-bowed ³⁵ curves connecting the sides. Oppositely disposed at the center of the top plate are two circular openings *l*, between which is a third circular opening *m*, through which passes a vertical pipe *n*, carrying at its upper end a ⁴⁰ horizontal pipe extending parallel to said plate and having its outer ends resting in circular recesses *o*, made in the upper ends of short uprights *p*, formed integral with the top plate.

⁴⁵ The letter *q* represents the jets, which are secured to the end portion of the horizontal pipe in such a position as to come over the circular openings in the top plate.

What I claim is—

⁵⁰ The herein-described design for a hydrocarbon-burner substantially as shown and described.

BENJAMIN N. HAWES.
